L. M. EGBERT

LATCH

Filed Nov. 26, 1923

FIG. 1

FIG. 2

INVENTOR.
LOUIS M. EGBERT.

BY

Louis M. Egbert

ATTORNEYS.

UNITED STATES PATENT OFFICE.

LOUIS M. EGBERT, OF INDIANAPOLIS, INDIANA.

LATCH.

Application filed November 26, 1923. Serial No. 677,042.

To all whom it may concern:

Be it known that I, LOUIS M. EGBERT, a citizen of the United States, and a resident of Indianapolis, county of Marion, and State of Indiana, have invented a certain new and useful Latch; and I do hereby declare that the following is a full, clear, and exact description thereof, reference being had to the accompanying drawings, in which like numerals refer to like parts.

This invention relates to a latching bolt particularly for use in latching floor boards in place so that there is no protuberance above the surface thereof.

The object of the invention is to provide a latch of the character which will herein-after be described for detachably securing removable parts in place, such as doors, windows, and particularly floor boards for vehicles, wherein it is desirable that there be no projection above the surface, the device being of simple construction so as to be capable of protection and installation, at low cost.

Other features and details of the invention will be hereinafter more fully described and claimed.

The full nature of the invention will be understood from the accompanying drawings and the following description and claims.

In the drawings, Fig. 1 is a plan view of a floor board held in place by the latching bolt. Fig. 2 is a side elevation thereof. Fig. 3 is an end elevation of the latch. Fig. 4 is a section taken on the line 4—4 of Fig. 3. Fig. 5 is a perspective view of the latching bolt.

In the drawings there is shown a floor board 10 adapted to be removably secured between the side pieces 11 of the floor of a vehicle; in which there is provided the usual recess 12 for receiving the end of the latching bolt.

The latching bolt as shown in Fig. 5 comprises a tooth edged engaging lip 13 which is formed integral with and protrudes from the end of the body of the bolt 14. On each side of the body portion 14 which acts as a guide and engaging means for operating the bolt, there are reduced flange portions 15 having the upper side thereof formed with ratchet teeth 16. On the upper surface of the body portion 14, there is provided a recess 17 which may be engaged with a screw driver or any other tool

for moving the bolt in and out of engaging position.

The bolt is mounted in a metallic housing 21 of sufficient breadth to receive the flange portions 15 and having an opening in the top thereof of proper dimensions to receive the body portion 14, whereby the latching bolt is held in place and capable of sliding longitudinally of the housing. The under side of the overhanging and inwardly extending portion of the housing adjacent the ratchet teeth 16 is provided with corresponding ratchet teeth 18. The bottom of the housing is provided with a recessed portion for receiving a plate spring 19 which is secured thereto at one end by the rivet 20. Said spring is so arranged as to engage the bottom of the latching bolt and normally force it under spring tension upwardly against the housing so as to maintain the ratchet teeth 16 and 18 in interlocking engagement; while yieldingly permitting the disengagement thereof by applying pressure to the body portion 14 and forcing the latch downwardly.

When it is desired to latch the floor board in place, a tool such as a screw driver is applied to the recess 17 and a forwardly but slightly downward pressure is exerted sufficient to cause the latch to slide forward into locking engagement with the recess 12. It will be locked in this position by reason of the spring 19 maintaining the ratchet teeth in engagement, thus preventing a rearward movement thereof. When it is desired to unlatch the floor board, the tool is applied to the recess 17 and a pressure exerted downwardly sufficient to overcome the spring tension of the spring 19, whereby the ratchet teeth will be disengaged, and then rearwardly to slide the bolt longitudinally of the housing and out of engagement with the recess 12, after which it will be held in unlatching position by re-engagement of the ratchet teeth.

It will be observed from the foregoing that the latching bolt will be maintained in either latching or unlatching position, so that vibration or jarring will not affect it. Furthermore, it is not necessary to employ any protruding element, thereby leaving the surface of the floor board clear. The latching bolt and its housing may be cheaply produced, as there are only two material parts, i. e., the bolt and the housing which can be readily cast, in addition to the leaf spring

which may be readily secured to the housing. As the floor board is cut to receive the housing, it may be driven in place without the use of screws or other securing means 5 and held therein by its wedging and dovetail formation. However, if desired, a securing screw may be readily placed in the bottom thereof.

The invention claimed is:

- 10 1. A latch comprising a bolt member, a housing member in which said bolt member is freely slideable, said housing member being provided with a longitudinal slot in the top thereof through which a portion of said 15 bolt member is adapted to extend, a ratchet tooth surface formed on the under side of the top of said housing member adjacent said longitudinal opening, a corresponding and engaging ratchet tooth surface on the 20 adjacent and upper surface of said bolt member, and yielding means mounted within said housing member and adapted to yield-

ingly bear against said bolt member for normally maintaining said adjacent ratchet tooth surfaces in interlocking engagement. 25

2. A latch comprising a bolt member provided with lateral reduced portions on each side thereof, ratchet teeth formed on the upper surface of said reduced portions, a housing in which said bolt is slidably mounted having inwardly extending portions provided with ratchet teeth on the under surface thereof, in position to engage and interlock with the ratchet teeth on said bolt, and a spring secured to the bottom of said 35 housing and exerting a yielding pressure upwardly against the bottom of said bolt for normally maintaining said ratchet teeth in interlocking engagement and permitting their disengagement. 40

In witness whereof, I have hereunto affixed my signature.

LOUIS M. EGBERT.
